UNITED STATES PATENT OFFICE

94,791

DESIGN FOR A TANK VEHICLE

Frederick G. Thwaits, Wauwatosa, Wis., assignor to The Heil Co., Milwaukee, Wis., a corporation of Wisconsin

Application October 1, 1934, Serial No. 53,440

Term of patent 14 years

To all whom it may concern:

Be it known, that I, Frederick G. Thwaits, a citizen of the United States, residing at Wauwatosa, in the county of Milwaukee and State of Wisconsin, have invented a new, original, and ornamental Design for a Tank Vehicle, of which the following is a specification, reference being had to the accompanying drawing, forming part thereof.

In the drawing:

Fig. 1 is a rear and side perspective view; and

Fig. 2 is a full rear view, showing my new design.

The dominant or important features of the design, including the relatively rectangular, transverse cross-section of the tank, are shown in solid lines, and the immaterial features are shown in dotted lines.

I claim:

The ornamental design for a tank vehicle, substantially as shown and described.

FREDERICK G. THWAITS.
